UNITED STATES PATENT OFFICE

148,412

DESIGN FOR A VENDING CART OR SIMILAR ARTICLE

Samuel Goodman, Chicago, Ill., assignor to Acorn
Sheet Metal Works, Inc., Chicago, Ill., a corporation of Illinois

Application November 14, 1946, Serial No. 134,787

Term of patent 14 years

(Cl. D14—3)

To all whom it may concern:

Be it known that I, Samuel Goodman, a citizen of the United States, residing at Chicago, in the county of Cook and State of Illinois, have invented a new, original, and ornamental Design for a Vending Cart or Similar Article, of which the following is a specification, reference being had to the accompanying drawing, forming a part thereof.

The figure is a perspective view of a vending cart showing my new design.

The dominant features of my design reside in the portion shown in full lines.

The remote side of the vending cart shown in the drawing is identical with that side which is visible.

I claim:

The ornamental design for a vending cart or similar article, substantially as shown and described.

SAMUEL GOODMAN.
